UNITED STATES PATENT OFFICE.

HENRY M. RICHARDSON, OF BOSTON, MASSACHUSETTS.

PARASOL-FRAME.

SPECIFICATION forming part of Letters Patent No. 296,354, dated April 8, 1884.

Application filed January 29, 1884. (No model.)

To all whom it may concern:

Be it known that I, HENRY M. RICHARDSON, a citizen of the United States, residing in the city of Boston, and county of Suffolk, and the State of Massachusetts, have invented certain Improvements in Parasol-Frames, of which the following is a specification.

The object of my invention is the provision of a parasol or umbrella frame which may be operated to open or close from its outer or upper side, or from the portion which in frames of common construction is provided with a walking post and ferrule; and it relates specifically to that class of frames which are employed in connection with children's carriages, although it is not necessarily restricted to such use.

In the drawings I have represented a good form of a convenient embodiment of my invention, Figure 1 being a view in perspective of the frame when open; Fig. 2, a side elevation of the same when closed; Fig. 3, a vertical sectional elevational detail of the sliding stem and thimble, especially illustrative of a convenient method of locking the frame in its open position; and Fig. 4, a perspective detail of the sliding stem and its spherical head.

Similar letters of reference indicate corresponding parts.

A is a thimble or tubular sleeve, through which the sliding stem B is free to travel as within a slide-bearing. The thimble is conveniently made of the form represented in the drawings—that is to say, saucer-shaped on top—and provided within the saucer with an annular boss, a, threaded on its peripheral exterior. At the base of the thimble is provided a collar, a^x, to which the upper extremities of the main ribs C C of the frame are pivoted or connected in any usual or convenient manner. b is a collar at the lower extremity of the sliding stem, to which are pivotally connected, in any usual or suitable manner, the inner extremities of the supplemental ribs D D. The sliding stem is swiveled, as at b^x, within the collar b, so that said stem is free to be rotated within said collar. The supplemental ribs are pivotally connected by the pivots d to the main ribs at suitable points about midway of the length of said main ribs after a manner usual in parasol-frames. At its upper extremity the

sliding stem is capped by a spherical or other shaped head, E, which is rigidly affixed thereto, and is provided with an annular socket, e, (clearly shown in Fig. 3,) threaded as to its exterior walls correspondingly to the threads upon the annular boss, about which said socket is adapted to be screwed by the rotation of the head and stem, which rotation the swivel of the stem permits.

Assuming the thimble to be held fixedly, the frame is either collapsed or expanded, respectively, by the drawing up or by the depression of the sliding stem through its thimble. When the stem is depressed until the boss encounters the socket, the rotation of the head and stem, securing the fixed engagement of the socket about the boss, will occasion an extra spread to the main ribs, and therefore impart an additional tension to the fabric on the frame, in addition to fastening the frame in its open position. The socket and boss are therefore not only a fastening device, but a device for imparting additional tension to the open parasol.

Other fastening devices may be substituted in the stead of the boss and socket, although the latter are preferable.

The device may be applied to any suitable supporting-standard sprung from the body of a carriage and overhanging the seat, the application being, if desired, by a ball-and-socket joint in such manner that the parasol-frame, when closed, may be flexed upward and backward, so as to cause the stem and its then collapsed ribs to assume a horizontal position in the direction either of the front, back, or sides of the carriage.

The mechanical structure of the thimble may, of course, be varied, and the means of pivoting the ribs thereto be such as convenience of manufacture may dictate, while the precise construction of the collar b and the swivel connection of the stem therewith may be varied at the will of the mechanic.

Having thus described my invention, I claim and desire to secure by Letters Patent—

1. The combination, to form a parasol-frame which can be opened or closed from the outside, of a thimble or hollow sleeve, to which the upper ends of the main ribs are connected, a sliding stem adapted to slide through the thim-

ble, to the lower portion of which stem are connected the inner ends of the supplemental ribs, and supplemental ribs attached to the stem and to the main ribs, substantially as set forth.

5. 2. The combination, to form a parasol-frame which can be opened or closed from the outside, of a thimble or hollow sleeve, to which the upper ends of the main ribs are connected, a sliding stem adapted to slide through the thimble, to the lower portion of which stem are connected the inner ends of the supplemental ribs, supplemental ribs attached to the stem and to the main ribs, and means for fixedly connecting the stem with the thimble, substantially as set forth.

15. 3. As a means for connecting the stem with the thimble and for securing additional tension to the expanded frame in a parasol-frame of the class herein recited, the combination of the threaded boss upon the thimble and the threaded socket connected with the stem, substantially as set forth.

4. The combination of the thimble, the rotatable stem, the main ribs, the supplemental ribs, the boss upon the thimble, and the socket 25 within the head of the stem, substantially as set forth.

5. In a parasol-frame, the combination of a thimble, main ribs pivoted at their upper extremities to said thimble and connected intermediate of their length to the respective outer extremities of auxiliary ribs, a stem adapted to slide within said thimble, and auxiliary ribs at their respective inner extremities, pivoted to a collar carried by the stem, and within 30 which said stem swivels, substantially as and for the purposes set forth.

In testimony whereof I have hereunto signed my name this 18th day of January, A. D. 1884.

HENRY M. RICHARDSON.

In presence of—

J. BONSALL TAYLOR,
W. C. STRAWBRIDGE.
